UNITED STATES PATENT OFFICE.

JEREMIAH A. PROCTOR AND JAMES B. MARTIN, OF UNION CITY, INDIANA.

FLOOD-FENCE.

SPECIFICATION forming part of Letters Patent No. 353,157, dated November 23, 1886.

Application filed June 12, 1886. Serial No. 204,931. (No model.)

To all whom it may concern:

Be it known that we, JEREMIAH A. PROCTOR and JAMES B. MARTIN, citizens of the United States, residing at Union City, in the county of 5 Randolph and State of Indiana, have invented certain new and useful Improvements in Water or Flood Gates; and we do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

15 This invention has relation to improvements in water or flood gates; and it consists in the construction and novel arrangement of devices, as will be hereinafter more fully set forth, and particularly pointed out in the claim 20 appended.

In the accompanying drawings, Figure 1 is a perspective view of a gate constructed according to our invention, and Fig. 2 is a view of the gate removed from the frame. Fig. 3 25 is a vertical sectional view showing the positions the gate assumes at low water and at flood.

Referring by letter to the said drawings, A indicates the mud-sill, which is arranged transversely in the bed of a stream. To the opposite ends of this sill are firmly secured in alignment two stout uprights, B B, constituting the main frame for the support of the gate. On the upstream side of the gate, and at a suitable distance above the base or mud-sill on 30 the uprights, are strongly secured at *a a* the upper ends of two vertical chains, C, the opposite ends of which are secured to the highest portions of the cylindrical log D, near opposite ends thereof.

The gate is composed of the transverse log D and the vertical pickets D', secured at their lower ends thereto. The log is annular in cross-section, and its ends extend sufficiently 45 to engage the uprights on the upstream side of the gate, and bear against the same when raised by a flood or the abnormal condition of the water in the stream. It will be observed

that the log in its normal position is held by the chains a sufficient distance above the sill 50 to permit an ordinary stream to pass without affecting the operation of the gate or removing it from its vertical position.

The weight of the log D and the points of attachment of the chains C to it should be so 55 adjusted with respect to the pickets D' that when there is no pressure against the latter they will maintain an upright position. (Shown in full lines, Figs. 1 and 2.) The points of attachment of said chains to the log 60 D should therefore be in the same plane as the line of pickets. By thus hanging the log directly from the upstream side of the posts B the natural tendency of the cylindrical ends of this log is to bear against these posts at all 65 times and to roll up them as the pickets are deflected from an upright position to the position indicated in broken lines, Fig. 3.

When a flood takes place, the rise in the stream will first act upon the log D, causing 70 it to rise and wind thereon the chains C. When the said log begins to rise in a rolling manner, the pickets will incline, and when the log has exhausted the chains it will be arrested by the fastenings *a a*, and the pickets will 75 have assumed a horizontal position and will remain firmly therein out of danger until the flood has subsided. As the flood subsides the base-log of the gate will unwind from the chains and the pickets return to a vertical 80 position.

We are well aware that it is not broadly new in flood-gates composed of a horizontal log and pickets secured perpendicularly thereto to suspend the gate by chains depending 85 from a horizontal bar between posts, the lower ends of which chains are secured to the log at points which are in a plane at right angles to the plane of the row of pickets, said logs being suspended free from said posts. We are 90 also aware that it is not new to hinge the base-log of a picket flood-gate to the upstream sides of posts, employing the upper ends of the posts or a cross-bar secured thereto as a stop for the gate when in a horizontal position. 95 Such devices we disclaim.

Having described this invention, what we claim is—

A tilting and floating flood-gate composed of a horizontal cylindrical base-log having 5 pickets rigidly secured to its upper side, in combination with suspension-chains, the lower ends of which are secured to the log on its upper side in the plane of the row of pickets, and the upper ends of said chains secured directly 10 to the sides of the supporting-posts, against which the cylindrical log bears, as set forth.

In testimony whereof we affix our signatures in presence of two witnesses.

JEREMIAH A. PROCTOR.
JAMES B. MARTIN.

Witnesses as to Jeremiah A. Proctor:

L. D. LAMBERT,
Z. T. OAKES.

Witnesses as to James B. Martin:
